UNITED STATES PATENT OFFICE

CHARLES A. MEALY, OF WEST BARRINGTON, RHODE ISLAND, ASSIGNOR TO THE HADLEY COMPANY, INC., OF PROVIDENCE, RHODE ISLAND, A CORPORATION OF RHODE ISLAND

WATCH-BRACELET CONNECTER

Application filed March 1, 1930. Serial No. 432,391.

This invention relates to bracelet connectors and pertains more particularly to improved means for separably connecting a bracelet end to a watch case or the like.

5 The principal object of the invention is to provide a detachable connector which may be inserted and anchored behind a constricted opening at the side of the watch case with a portion of the connector projecting through 10 the opening for attachment to a bracelet end. The anchored portion of the connector may thus be concealed by the watch case within a pocket or recess which is accessible by removing a portion of the case or which may have 15 an open bottom permitting the connector to be applied without separating the watch case.

The connector herein described is particularly adapted for use with an open link bracelet of the type disclosed in a copending application Serial No. 426,304, filed February 6, 1930, by myself and another joint inventor; and the link connecting elements covered in said application are employed in the recommended embodiment of the present invention, 20 which is illustrated in the accompanying drawings, for attaching the projecting portion of the removable connector to the end link of the bracelet after the bracelet length has been properly adjusted by adding or removing links. It will be understood however 25 that my improvement may be employed with other forms of bracelet without departing from the spirit of my invention as defined in the appended claims.

30 In the drawings:

Fig. 1 is a plan view of a link bracelet attached to a watch case by my improved connecting means;

Fig. 2 is a section on line 2—2 of Fig. 1;

Fig. 3 is a similar view illustrating one mode of removing the connector from the watch case after removing the back of the case and the watch movement;

Fig. 4 is a similar view showing the manner of separably attaching the projecting end of the connector to the end link of the illustrated bracelet, and also illustrating a modification in the watch case; and

Fig. 5 is a perspective view of the connector.

As more fully described in said copending application, the bracelet shown in the drawings comprises a plurality of open links 6 separably interlocked by connecting elements including a member 7 straddling the side bars 8 of adjacent links and a locking piece 9 removably interfitting in channels 10 of said member. The locking piece slides endwise into the base of the member 7 and is held in position by friction or by supplementary fastening means, thereby to enclose the side bars of the links within the connecting member. The bracelet shown in said application is provided with an end hook which is fastened upon a projecting bail or loop of a watch case; and the principal purpose of the present invention is to avoid a visible connection of the former type by concealing the anchored portion of the connector within a pocket or recess constituting a part of or an adjunct to the watch case.

Accordingly, the watch case 11 herein illustrated is provided with a normally closed pocket 12 which is accessible after removing the back of the case and which has a constricted opening or slot 13 leading therefrom through the side 14 of the case. The back 15 of the watch case may be pivotally or detachably mounted upon the body portion 11 thereof in any usual manner, and the front or bezel of the case may be integral with said body portion or separable therefrom, all in accordance with common practices.

The connector 16 preferably comprises a piece of sheet metal having a transverse slot 17 adjacent one end and an anchoring portion 18 which may be formed by rolling the metal stock into a tube, at its opposite end. The slot 17 may be conveniently provided by striking a tongue 19 from the metal blank and folding the tongue backwardly upon the outer margin of the connector. When applied to the watch case, the slotted end of the connector projects outwardly through slot 13, while the enlarged anchoring portion 18 is retained within the pocket 12 behind the constricted opening, the diameter of the tube being greater than the width of the slot. The projecting end may be at-

tached to the end link of the bracelet by the separable connecting elements 7 and 9 in the same manner as the elements are applied to adjacent links of the bracelet. For example, member 7 may be passed through the opening 17 in the connector (Fig. 4) and over the side bar 8 of the end link 6, and the locking piece 9 may then be slid endwise into the guide channels of member 7 to close the bottom of said member (Fig. 2). Accordingly the connector 16 affords a secure but readily separable attachment for connecting the bracelet to the watch, and it is apparent that the connector may be employed with bracelets formed of leather or fabric straps, metal mesh or solid metal bands, as well as link bracelets.

It is also obvious that the particular construction of the watch case is not essential to this invention, provided that the case has a constricted slot or opening through which a portion of the connector may project outwardly and that the inner end of the removable connector is anchored behind said opening within a recess or pocket of the case which is accessible from the back of the case to permit insertion or removal of the connector. The watch cases shown in the drawings are accordingly merely illustrative of this invention, and their structure may be modified as desired without sacrifice of the efficiency of the improved connection. The case of Figs. 1, 2 and 3 is provided with a detachable back 15 which encloses and entirely conceals the anchoring portion within the case; whereas in Fig. 4 the back 20 of case 21 terminates short of the wall 14 leaving the bottom of the pocket 21 open.

In order to insert or remove the connector from the case of Figs. 1 to 3, it is necessary to detach the back 11 and, in some cases, also to remove the watch movement 22 as indicated in Fig. 3; but in the structure of Fig. 4, the connector may be applied or removed through the open bottom of the pocket without separating the watch case. In either instance the connector 16 is removably anchored within the watch case and only a relatively small portion is visible after the bracelet is attached to its projecting end. As above described, said projecting end preferably has a slot or opening to receive a separable attachment for connecting the bracelet end thereto, but any common form of attachment may be employed, as desired.

It is thus apparent that the principal feature of this invention is the provision of a connector which may be removably applied to a watch case with its outer end projecting through an opening in the side of the case for separable attachment to a bracelet end and its inner end anchored behind said recess and concealed within the case, at least when the watch is applied to the wrist. A connector of the type described is of simple

construction and furnishes an attachment of pleasing and distinctive appearance which is durable in use and efficient in operation, and which may be applied or removed with ease.

I claim:

1. A watch case or the like provided with an interior recess and a constricted opening leading outwardly therefrom, a removable connector having its outer end projecting through said opening and its inner end anchored in said recess, and a bracelet separably attached to the projecting end of the connector. 70

2. A watch case or the like provided with an interior recess and a constricted opening leading outwardly therefrom, a connector having an enlarged portion anchored behind the opening within said recess and an end portion projecting outwardly through said opening, the anchored portion being concealed by the front of the watch case and being removable from the case by withdrawing its portion inwardly through the opening, and a bracelet separably attached to the projecting end of the connector. 80

3. A watch case or the like provided with an interior recess and a constricted opening leading outwardly therefrom through the side of the case, a connector having an end portion smaller than the opening projecting outwardly through said opening and having an enlarged inner end anchored in the recess behind the opening, the connector being removably insertable through the interior of 100 the watch case, a bracelet, and means for separably attaching the bracelet end to the projecting portion of the connector. 95

4. A watch case or the like provided with an interior recess and a slot leading outwardly therefrom through the side of the case, the recess being accessible from the interior of the case, a removable connector formed of sheet metal and having a flat end portion projecting outwardly through said slot and a 110 rolled portion at its opposite end, the diameter of the rolled portion being greater than the width of the slot to anchor the inner end of the connector within the recess, and the flat outer end of the connector having an opening therethrough, a bracelet, and means passing through said opening for separably attaching the bracelet end to the connector. 115

Signed by me at Providence, Rhode Island, 120 this 19th day of February, 1930.

CHARLES A. MEALY.
